FOUNDATION GARMENT

Elsa E. Bertrams, Chicago, Ill., assignor to Kabo
Corset Co., Chicago, Ill., a corporation of
Illinois

Application July 3, 1935, Serial No. 29,612

8 Claims. (Cl. 2—30)

This invention relates to an improved foundation garment, and has for one of its principal objects the provision of a garment of this sort which shall readily adapt itself to the contours of the body in all positions and which shall, at the same time, be automatically prevented from getting out of shape.

One of the important objects of this invention resides in the provision of a foundation garment 10 or corset, having a shiftable reinforced element which is applied in conjunction with certain elastic portions of the garment whereby, while the elasticity is retained, undue stretch and undesirable expansion of certain portions of the body at adjacent points is prevented.

Another and further important object of the invention is to provide a corset having resilient portions capable of being stretched in all directions, these resilient portions being supplemented 20 by a reinforcement or guard which retains the desired body contours while, at the same time, allowing of an elastic supporting of the body portions such as the hips, buttocks, and the like.

Still another object of the invention is to provide combination garter supports and resilient tape means for connecting the reinforcement or guard to the main body portion of the corset at the lower edges thereof.

Another object is to provide a combination of 30 non-resilient material, one-way stretch material, and two-way stretch material in a garment so as to provide adequate support for the corresponding portions of the body with due regard for comfort and proper fitting.

A still further object is the provision, in a garment of this type, of means for resiliently connecting the non-resilient reinforcing panel, which constitutes one of the main features of the device, to the garters which support the hose of the wearer.

An additional object is the inclusion of means which prevent the garment from riding up on the body or figure of the user.

Other and further important objects of the invention will be apparent from the disclosures in the accompanying drawing and following specification.

The invention, in a preferred form, is shown in the drawing and hereinafter more fully described.

In the drawing:

Figure 1 is a plan view of the improved corset of this invention, showing the same opened and illustrating particularly the inside reinforcement 55 or supporting element which forms one of the main features of the invention.

Figure 2 is a sectional view taken on the line 2—2 of Figure 1, looking in the direction indicated by the arrows.

Figure 3 is a perspective view showing a por-

tion of the corset as fitted to the body of a wearer, illustrating particularly the action of the improved reinforcement and adjacent parts.

Figure 4 is an elevational view of the upper part of the rear portion of the garment, showing particularly the combination of one-way stretch material with two-way stretch material.

As shown in the drawing:

The reference numeral 10 indicates generally the front portion or panel of a corset or similar garment, this being preferably composed of non-resilient material such as suitable cloth or the like which, however, may be supplemented at its lower middle portion by an insert of elastic or resilient material 12 which elastic material is 15 preferably capable of being stretched in only one direction.

At the top of the front portion 10 of the corset is provided a suitable brassière attachment or the like 14 for the retention and support of the breasts of the wearer, and suitable shoulder straps 16 are provided attached to the top of the brassière portion and adapted to be removably applied to buttons or the like 18 at one end and to similar buttons 20 on short straps at the rear of the corset.

Along one edge or side of the front portion of the corset 10 is provided a line of hooks or the like 22 adapted to be fitted into corresponding eyes (not shown) at the other edge 24 of the garment.

The rear of the garment is provided with a top portion 26 which is preferably of somewhat the same material as the front portion 10, being non-elastic but which may be fitted with an insert 28 similar to the insert 12 in the front portion.

The bottom portion of the rear of the garment is composed of resilient material 30 capable of stretching in any and all directions, and this is 35 the portion of the garment adapted to encompass and retain the hips or buttocks of the wearer.

This elastic material 30 capable of being stretched in all directions is likely to become somewhat out of shape after repeated use and continuous wearing, particularly in the case of larger women, and to this end, a reinforcement therefor is provided in the form of a panel or the like 32 composed of non-resilient cloth or similar material. This panel is attached at its top to the garment by means of lines of resilient stitching 34, and extends along and substantially covers the inner face of the rear portion of the garment, particularly that portion which is composed of the two-way stretch material 30. If desired, this reinforcing panel may be supplemented by stays 55 or the like 38 built therein as best shown in Figures 1 and 2, and these stays may be of any suitable material such as metal or the like.

As best shown in Figures 1 and 2, the panel 32

is not attached to the material 30 throughout the entire extent of its upper edge by the stitching 34, the connections being only at certain points, namely the outside corners of the upper edge, and 5 it will be further obvious from an inspection of Figures 1 and 2 that the U-shaped portion of the upper part of the panel 32 is cut away so that a stretch can result along the line 34. Also as best shown in Figure 2, the portion 26 with 10 its stretchable insert 28 is separate from the two-way stretch material 30, and is fastened thereto only at points behind the stays 38 in the non-resilient panel 32. This particular part of the structure is also best shown in Figure 4.

15 The lower end of the reinforcing panel 32 is free from the remainder of the garment except for attachments at the corners 40 consisting of strips of resilient or non-resilient tape or the like 42 which connect the lower corners of the 20 panel to corresponding portions of the flexible back panel 38 as best shown in Figure 1. Suitable garter connections 44 are provided for attachment to stockings 46, and these garter connections also assist in retaining the garment itself 25 in proper position.

30 Garter elements 44 are slidably fitted on the resilient tapes 42 so that they will automatically adjust themselves to the position of the wearer, and the tension on the garment and the stockings 46 as best shown in Figure 3.

It will be obvious that herein is provided a foundation garment, corset or girdle which, in addition to combining all the advantages of a two-way stretch material, also includes reinforcing means which prevent undue stretch of this 35 material at certain points of the body, while at the same time allowing of a perfect freedom of movement and operation, and providing a shapely figure or contour. Additionally, the operation of the reinforcement is automatic in that it requires 40 no attention whatsoever, and will immediately and instantly adapt itself to any posture of the body whether sitting, standing, or walking, or any other movement, while at the same time the desired shapeliness is attained and maintained.

45 I am aware that many changes may be made and numerous details of construction varied throughout a wide range without departing from the principles of this invention, and I, therefore, do not purpose limiting the patent granted hereon otherwise than as necessitated by the prior art.

I claim as my invention:

1. A corset, including a back section of resilient material, and a reinforcing panel of non-resilient material supplementing the resilient section and positioned thereover, the reinforcing panel being attached at portions of its upper edge to corresponding portions of the resilient material, the sides and lower edge of the reinforcing panel being free from the resilient structure.

60 2. A corset, including a back section of resilient material, and a reinforcing panel of non-resilient material supplementing the resilient section and positioned thereover, the reinforcing panel being attached at portions of its upper edge to corresponding portions of the resilient material, the sides and lower edge of the reinforcing panel being free from the resilient structure but 65 with resilient tape connections extending from and connecting one to the other.

3. In a corset having attached garters, resilient means for encircling and supporting the buttocks, said resilient means being capable of stretch in two directions, and a reinforcing non-resilient element positioned on the inner face of 5 said resilient means and attached thereto at spaced points along its upper edge, and connections between the non-resilient element and the buttock encircling resilient means for transmitting pull and strains from the non-resilient element to the garters.

4. In a corset having attached garters, resilient means for encircling and supporting the buttocks, said resilient means being capable of stretch in at least two directions, and a reinforcing non-resilient element positioned on the inner face of said resilient means and attached thereto at spaced points along one edge, the panel having a cut-away portion between said points, and connections between the non-resilient element 20 and the buttock encircling resilient means for transmitting pull and strains from the non-resilient element to the garters.

5. In a corset, resilient means for encircling and supporting the buttocks, said resilient means 25 being capable of stretch in at least two directions, and a reinforcing non-resilient element positioned on the inner face of said resilient means and attached thereto at opposed corners of its upper edge, flexible tapes attaching the corners 30 of the lower edge of the non-resilient element to the resilient means and garter connections on said flexible tapes.

6. A body garment, including an upper rear portion, a lower rear portion of resilient material capable of stretching in both directions, said upper portion overlapping the lower portion, and a reinforcing panel over a desired area of said lower portion, said reinforcing panel being attached thereto but free therefrom over its surface, the 40 attachment comprising a line of resilient stretchable stitching at the top thereof, and a cut-away portion in the panel adjacent the line of stitching to provide additional resiliency.

7. In a corset having attached garters, resilient means for encircling and supporting the buttocks, said resilient means being capable of stretching in at least two directions, a waist piece above and overlapping the buttock encircling means, and a reinforcing non-resilient fabric 50 panel positioned on the inner face of said resilient means, and connections between the non-resilient panel and the resilient buttock encircling means, said connections transmitting pulls and strains from the non-resilient element to the 55 garters.

8. In a corset having attached garters, an upper encircling element, resilient means for encircling and supporting the buttocks, said resilient means being capable of stretching in at least two 60 directions, and a reinforcing non-resilient fabric panel positioned on the inner face of said resilient means and attached thereto along one edge, the waist encircling means, the buttock supporting means, and the reinforcing panel being 65 interconnected but independently movable with respect to each other, and resilient connections between the non-resilient fabric panel and the resilient buttock encircling means, said connections transmitting pulls and strains from the 70 non-resilient element to the garters.

ELSA E. BERTRAMS.
